US00D916700S

(12) United States Design Patent (10) Patent No.: US D916,700 S
Li et al. (45) Date of Patent: * Apr. 20, 2021

(54) WRIST SMARTPHONE

(71) Applicant: BEIJING XIAOMI MOBILE SOFTWARE CO., LTD., Beijing (CN)

(72) Inventors: Ningning Li, Beijing (CN); Yingchun Xie, Beijing (CN); Jing Jiang, Beijing (CN); Zhi Fan, Beijing (CN)

(73) Assignee: Beijing Xiaomi Mobile Software Co., Ltd., Beijing (CN)

() Term: 15 Years

(21) Appl. No.: 35/508,576

(22) Filed: Oct. 21, 2019

(80) Hague Agreement Data

Int. Filing Date: Oct. 21, 2019

Int. Reg. No.: DM/205724

Int. Reg. Date: Oct. 21, 2019

Int. Reg. Pub. Date: Feb. 14, 2020

(30) Foreign Application Priority Data

Apr. 22, 2019 (CN) 201930186883.3

(51) LOC (13) Cl. 14-02

(52) U.S. Cl.

USPC D14/344
